REINFORCEMENT AND SPRING CLIP CONSTRUCTION FOR BILLFOLDS

Original Filed Feb. 5, 1942

UNITED STATES PATENT OFFICE

2,455,515

REINFORCEMENT AND SPRING CLIP
CONSTRUCTION FOR BILLFOLDS

Samuel Miller, Kew Gardens, N. Y.

Substituted for abandoned application Serial No.
429,590, February 5, 1942. This application
November 6, 1945, Serial No. 626,925

1 Claim. (Cl. 150—38)

1

This invention relates to devices for removably holding articles such as papers or bills, and has particular reference to compact, portable or pocket devices, such as billfolds.

The present application is a substitute for my application Serial No. 429,590, filed February 5, 1942, for Billfolds.

One object of the invention is to provide a device of the character described having improved means whereby articles can be removably retained in a particularly simple and compact manner.

Another object of the invention is to furnish a folder or similar device having improved means to facilitate the folder action and to releasably retain articles therein.

Another object of the invention is to construct a device such as a billfold having a simple spring clip and a holder therefor serving the correlated functions of holding bills or papers and of providing compactness, simplicity, decorativeness and reinforcement for the billfold, as well as greatly reducing its cost of manufacture.

Other objects and advantages of the invention will become apparent as the specification proceeds.

With the aforesaid objects in view, the invention consists in the novel combinations and arrangements of parts hereinafter described in their preferred embodiments, pointed out in the subjoined claim, and illustrated in the annexed drawing, wherein like parts are designated by the same reference characters throughout the several views.

In the drawing:

Figure 1 is a view in side elevation showing a device embodying the invention.

Fig. 2 is a top plan view thereof.

Fig. 3 is an enlarged sectional view taken on the line 3—3 of Fig. 1.

Fig. 4 is a perspective isometric view of the device in open position showing in dot-dash lines a bill secured therein, and indicating in dot-dash lines the slidability of the clip.

Fig. 5 is a view in side elevation of a modification of the invention.

Fig. 6 is a top plan view thereof.

The advantages of the invention as here outlined are best realized when all of its features and instrumentalities are combined in one and the same structure, but, useful devices may be produced embodying less than the whole.

It will be obvious to those skilled in the art to which the invention appertains, that the same may be incorporated in several different con-

2

structions. The accompanying drawing, therefore, is submitted merely as showing the preferred exemplification of the invention.

Referring in detail to the drawing, 10 denotes a device embodying the invention, and being illustrative of an article holder or folder, such as a billfold. The same may comprise a wall on which various articles or papers may be mounted. This wall may include a plurality of sections or leaf-like plates or members 12 which are angularly movable toward and away from each other in closing and opening the device. As a binding or fold maintaining means, I may employ a metallic tube 13, which may be open ended, and split along a line 14 to provide confronting clamping edges or jaws at the split. This tube extends along an edge of said walls 12 and receives therein marginal portions 15 of the members 12. By clamping the tube on said marginal portions, the members 12 are permanently secured together by the tube jaws at 14. The clamping operation may be facilitated by partially or temporarily securing together the members 12 so that they will not accidentally shift relative to each other during the clamping. If desired, the members 12 may be sewn together along a line coincident with the split 14, before the members are engaged with the tube 13. Moreover, the members 12 may consist of a single sheet folded, with its fold edge portion engaged in the tube 13, but this may be undesirable, because it may require a larger tube 13, and because the leather or composition materials of which the members 12 may consist, although flexible, may wrinkle or distort, and require additional care and labor in manufacture.

It is noted that the tube 13, in combination with the adjacent part of the members 12, affords an external tube structure 16, the metallic part 40 of which is ornamental, and is continuously uniformly engaged with the members 12 to provide a neat device, which is reinforced by the tube 13. Since the latter may be quite small in diameter, compactness is maintained, and yet a powerful binding results which can be constructed very cheaply.

Co-operating with the tubular structure 16 is an article holding means such as a U-shaped spring clip 17 having a pair of arms 18, 19 which 50 are resiliently urged toward each other, and having a bight portion 20. The said arms may be alike, but preferably the arm 18 is relatively straight for easy sliding insertion into the tube 13 whereas the arm 19 is disposed inside of the device 10 as between the members 12, and

serves as a holder for various articles such as papers or bills. Accordingly the bight portion 20 extends across the wall 11 at an end thereof and may form an ear whereby the device 10 may be suspended for display and other purposes. To facilitate the action of the arm 19, the same may have an outwardly turned finger 21, and, if desired, it may be bowed to provide a plurality of spaced pressure areas at 22, 23 for securely frictionally holding the papers or bills. The spring clip may be a conventional bobby pin.

Because the clip 17 bears as at 15 on the leather or other fibrous material of the leaves 12, there is a frictional engagement which supplements the rigid, relatively permanent binding afforded by tube 16. The portions of the leaves lying within the tube afford a body greatly augmenting the mass engaged in the clip ensuring a secure engagement, this mass being highly yieldable, because the clip acts angularly thereon, to thus accommodate the clip when a large or a small number of bills are held thereby. The clip is thus reliably continuously engaged along its path of movement, the area of frictional engagement with the inner parts of the leaves being a maximum when the clip is moved into bill clamping position as shown in full lines in Fig. 4.

It will be noted that the arm 18 may be removably retained in the tube 13 or permanently connected therewith, and in either case, the spring clip 17 may be slid up and down as suggested in Fig. 4 to aid in passing the holder arm 19 over a paper or bill and to facilitate removal of the same. However, the spring clip 17 may be permanently maintained in its lowered position as shown in Fig. 1. In that case, the bills such as 24 are slid up or down under the holder arm 19 for insertion and removal of the bills.

The arm 18 may seat itself between the marginal portions 15 of the members 12, as shown in Fig. 3, so as to press these marginal portions apart to thus afford additional securement against any accidental release of the members from the clamping tube 13. If the leaves 12 consist of a single folded sheet, then the clip bears upon the fold which is thus flattened down against the tube.

Since the holder arm 19 lies between the members 12 and closely adjacent to the tube 13, the angular position of the spring clip is relatively fixed, and the arm 19 is caused to bear against that part of the wall 11 which is strongly backed by the tube 13. Because of the flexibility of the members 12, they are adapted to readily bend and conform about the arm 19 with said members lying quite close together in the closed position of the device.

In Figs. 5 and 6 is shown a modification wherein a device 25 embodies the principles of the device 10 but possesses the additional advantages of affording a plurality of compartments in

a highly compact manner. Thus the wall 11a is arranged to form a Z in cross section, as shown in Fig. 6, thus affording outer leaf-like members 26 and an intermediate leaf-like member 27 which is desirably of greater length than the former, so that the tubular structures 16a which may be like those at 16, are exposed and free of the adjacent free edges of the members 26. Thus a plurality of compartments 28 are provided which may be used to hold different papers or bills of different denominations, each compartment being constructed alike and being operative in the same manner as the billfold 10. The device 25 has the further advantage of being reinforced at opposite ends by the tubular structures so that it will not wrinkle or curl in the pocket of the user.

I claim:

A billfold having a plurality of separate leaves of pliable material, a one-piece binder tube of rigid material extending substantially the full length of the leaves and being split from end to end thereof to provide uniformly spaced free-edge jaws, the leaves having sections thereof permanently clamped between said jaws, these sections having portions projecting inward of the tube beyond the jaws and providing a flexible body in the tube, and a U-shaped spring clip having a crotch portion at an end of the split tube, one arm of the clip being external of the tube and lying freely exposed between the leaves so as to be adapted to be sprung over bills disposed in the billfold, the other arm of the clip being housed in the tube in overlying relation to said flexible body and being thus retained by the tube in cooperation with the external portions of the leaves between which the outer arm lies, the said flexible body extending substantially from end to end of the split tube and the clip being movable at least partially longitudinally of the tube in snug, frictional engagement with the said flexible body to prevent accidental removal of the clip.

SAMUEL MILLER.
